James F. Williamson

UNITED STATES PATENT OFFICE.

OLOV WALLO, OF MINNEAPOLIS, MINNESOTA.

CLOTHES-LIFTING DEVICE FOR BOILERS.

Application filed March 13, 1924. Serial No. 698,921.

To all whom it may concern:

Be it known that I, OLOV WALLO, a subject of the King of Norway, residing at Minneapolis, in the county of Hennepin and State of Minnesota, have invented certain new and useful Improvements in Clothes-Lifting Devices for Boilers; and I do hereby declare the following to be a full, clear, and exact description of the invention, such as will enable others skilled in the art to which it appertains to make and use the same.

This invention relates to a lifting or handling device for articles contained in a boiler or similar receptacle. While the invention may be used to handle any articles which are boiled in a receptacle or handled in hot water, it is particularly designed for handling or lifting clothes when the same are being laundered. As is well known, it is customary to boil the clothes and it is quite inconvenient to lift the same from the boiling water by hand or by means of the round stick often used.

It is an object of this invention, therefore, to provide a simple and efficient container adapted to hold the clothes during the boiling operation by means of which they may be placed in and moved from the boiler with rapidity and convenience.

It is a further object of the invention to provide such a device comprising a member formed of sections of flexible perforate material, which member is arranged to fit within a boiler and to be supported therein.

It is still another object of the invention to provide such a holding device for clothes or other articles having flat or tapered end portions, together with means for closing said end portions.

These and other objects and advantages of the invention will be fully set forth in the following description made in connection with the accompanying drawings in which like reference characters refer to the same parts throughout the different views, and in which,

Fig. 1 is a view in front elevation of a boiler of common construction showing the device in use therein, a portion of said view being in vertical section;

Fig. 2 is a top plan view of Fig. 1;

Fig. 3 is a horizontal section on the line 3—3 of Fig. 1, as indicated by the arrows;

Fig. 4 is a developed plan view of the holder; and

Fig. 5 is a view of the closed loop used in the device.

Referring to the drawings, a boiler of oblong or flattened cylindrical shape is indicated as 1, which, preferably, will be of suitable metal. The holding device is shown generally as 2 and the same comprises sections 3 and 4 of flexible perforate material. While the device can be made of various materials, a strong netting of cord or flexible wire preferably is used. The sections 3 and 4 have central portions of substantially rectangular shape and, as shown in Fig. 4, the sections are alternately disposed and have their adjacent sides secured together, said sections thus forming a receptacle with closed sides. Said receptacle is held in the desired shape at the bottom by being secured to a loop 5 shown in detail in Fig. 5. While this loop may be of any desired shape to fit the boiler used, in the embodiment of the invention, it is shown as oblong to fit the boiler 1. The sections 3 are also provided with tapered end portions which, as will be seen in Figs. 2 and 3, are adapted to be folded or drawn together and to close the ends of the receptacle. The terminal ends of said portions are provided

with eyelets 6, which eyelets are traversed successively by a flexible member such as a cord 7 so that they may be drawn together to cause the ends of the sections to approach and close the end of the receptacle. The cord 7 is held in position to hold the end closed by a friction clamp 8 which frictionally engages the strands thereof and which can be moved close to the eyelets 6. The eyelets at the top of the receptacle are also traversed by a flexible member of cord

9, one end of which is secured to one of the eyelets through which the other end passes after having traversed all of the other eyelets. The latter end of the cord may be carried upwardly through an eyelet 10 or other suitable member above the boiler 1 so that the free end of the cord may be pulled upon to lift the receptacle. The sections 3 and 4 have secured thereto adjacent the tapered upper ends a series of hooks 11 adapted to extend up and hook outwardly over the top edge of the boiler 1.

In operation, the receptacle 2 will be dis-

posed either in or out of the boiler 1, the cord 9 will be released and the end portions of the sections 3 and 4 drawn back to open the top of the receptacle. The articles to be treated, such as the clothes *a*, will then be disposed in the receptacle. The cord 9 will now be drawn upon and will cause the top sections of the receptacle to approach so as to close the top thereof. If the receptacle is disposed without the boiler, the same can now be raised by pulling on the cord or rope 9 and the receptacle swung over the boiler and lowered into the same. As it is placed in the boiler, the hooks 11 can be engaged over the edges of the boiler. The receptacle is now retained in proper shape and substantially fits the interior of the boiler 1. After the boiling is completed, the rope 9 can again be pulled upon to raise the receptacle from the boiler and allow the water to drain from the clothes. After the draining is completed, the receptacle can be swung to the desired point and over another receptacle, if desired, and the friction member 8 slid outwardly on the cord 7. This will allow the lower end sections of the receptacle to diverge so that the clothes may be discharged as desired. The lower end of the receptacle can then again be closed and the operation repeated.

From the above description it is seen that applicant has provided an extremely simple, efficient and inexpensive device for handling articles to be boiled or treated in hot liquid. The device is easily made and can be conveniently and quickly manipulated.

It will, of course, be understood, that various changes, may be made in the form, details and arrangement of the device without departing from the scope of applicant's invention, which, generally stated, consists in such a device as shown and described and defined in the appended claims.

What is claimed is:

1. A device for handling articles in liquid comprising sections of perforate flexible material connected to form a container with closed sides, a closed loop of rigid material at one end of said container, said sections having end portions adapted to be drawn

together to close the end of said container, and means for drawing said portions together at each end of said container.

2. A handling and lifting device for articles to be placed in hot water comprising sections of flexible perforate material connected to form a container with closed sides, a closed loop of substantially rigid material at one end of said container, said sections having tapered end portions adapted to be drawn together with the sides substantially in contact to close the ends of said container, means for drawing said portions together at the lower end of said container, and means for drawing said portions together at the upper end of said container and for lifting said container.

3. A clothes handling device comprising sections of reticulated flexible material having rectangular central portion connected at their sides to form a closed container, said sections having tapered end portions, and means for drawing said end portions together to close the ends of said container.

4. A lifting device adapted to be disposed in a boiler comprising sections of flexible perforate material connected to form a container with closed sides, a stiffening loop connected to one end of said container, spaced hooks at the other end of said container adapted to hook over the edge of a boiler, and means for closing each end of said container.

5. A device adapted to hold articles to be treated in hot water comprising sections of reticulated flexible material having rectangular central portions connected at their edges to form a receptacle with closed sides, said sections having tapered end portions, eyelets at the terminals of said portions, flexible means extending through said eyelets at one end of said receptacle adapted to draw said portions together, and flexible means extending through the eyelets at the other end of said receptacle to draw said portions together and lift said device.

In testimony whereof I affix my signature.

OLOV WALLO.
